UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

APPARATUS FOR DRYING MATRICES.

1,286,477.

Specification of Letters Patent.

Patented Dec. 3, 1918.

Original application filed February 23, 1911, Serial No. 610,234. Divided and this application filed December 21, 1916. Serial No. 138,225.

To all whom it may concern:

Be it known that I, HENRY A. WISE Wood, a citizen of the United States, residing at New York, in the county of New York and State of New York, have invented a new and useful Apparatus for Drying Matrices, of which the following is a specification.

This is a division of my application for patent Serial No. 610,234, filed February 23, 1911.

This invention relates to the drying of stereotype matrices. The principal objects of the invention are to provide an apparatus for drying such matrices in a continuous uninterrupted operation by the employment of mechanism moving with the matrices so as to make the operation short and exact, thereby uniformly drying the matrices and saving much space and time in the operation; to provide moving means whereby the necessary pressure can be applied to the drying blankets in a uniform manner throughout the drying operation; and to provide means whereby the friction between the blankets and the pressing means can be reduced so as to prevent the creeping of the blankets and matrix.

Further objects and advantages of the invention will appear hereinafter.

Reference is to be had to the accompanying drawings in which—

Figure 1 is a side elevation of a machine embodying one form of this invention;

Fig. 2 is a sectional view on the line 2—2 of Fig. 1;

Fig. 3 is a side view of a form, blanket, etc., used with the form of the invention shown in Fig. 1;

Fig. 4 is an end view thereof;

Fig. 5 is a side view similar to Fig. 1 showing a modification;

Fig. 6 is a sectional view of the same on the line 6—6 of Fig. 5, and

Fig. 7 is a vertical longitudinal sectional view on enlarged scale of a form and accompanying parts suitable to be used with the form of the machine shown in Figs. 5 and 6.

Referring first to the first four figures,

the invention is shown as embodied in a form in which the matrix heating device proper comprises a stationary steam table 10. This steam table has a plane surface on the top on which the forms 11 are adapted to rest and along which they can be moved by hand or power. In the present instance each form is shown as having a pin 12 on each side and two endless chains 13 are provided having hooks 14 at intervals for engaging the pins and moving the forms along the table. The endless chains are shown as driven by a motor 15, shaft 16, worm 17, and worm wheel 18 on a shaft 19 on which two of the sprocket wheels 20 are located. The details of the driving mechanism are not shown herein. Any desired kind of mechanism can be employed for driving the chains either continuously or intermittently as desired.

In this form of the invention a second pair of chains 35 are employed driven in any desired way and having thereon pressure plates 36. The two chains are spaced and driven so that the pressure plates will be advanced with the forms as they are moved forward by the hooks 14. In the use of the device the forms are placed at one end of the table as they are received ready for drying. The blankets can be laid on the forms by hand before or after they are placed on the table. The endless chains being started, the hooks 14 thereon will engage the pins 12 and move the forms along. As the forms progress, they are thoroughly heated from below and the moisture is driven from the matrices into the blankets which are under pressure on account of the position of the upper chain. It is to be observed that the pressure exerted on the blankets and matrix will be substantially uniform throughout the heating operation. The chains leave the forms on the other end of the table, from which they can be removed at will.

The blankets are attached to the pressure plates by means of clamps 37 shown in Figs. 3 and 4. These clamps are operated by means of an eccentric shaft 38 and an operating arm 39 thereon. This shaft has

holes 44 for the reception of the end of a rod for turning the shaft.

In this case the pressure is obtained by means of a fixed bar 40 having a spring-
5 pressed shoe 41 thereon, in contact with the pressure plates as they are moved along. The compression of the springs 42 tends to press the blankets into the matrix. The shoe 41 is held in place by headed studs 43
10 which connect it with the stationary bar 40 and prevent its falling too low to engage the tops of the pressure plates as they are moved around. These traveling pressure plates also prevent the matrix and blankets
15 from creeping.

In the form shown in Figs. 5, 6 and 7, similar conditions prevail as in Fig. 1, but in this case the creeping of the blankets and matrix is prevented and the friction reduced
20 by the use of an endless belt 45 which runs between the fixed shoe 46 and the pressure plates 47 which are located above the matrices. These pressure plates are supported by springs 48 from plates 49 that rest directly
25 on the blankets. They are held in position and their upward motion limited by headed studs 50.

It will be seen that in all the forms shown the matrices can be dried quickly and uniformly under a perfectly uniform pressure and that the devices for reducing friction while not absolutely necessary add greatly to the efficiency of the device.

While I have illustrated and described
30 only two forms in which the invention can be embodied, I am aware of the fact that the drawings do not exhaust all the ways in which the invention can be carried out and therefore, I do not wish to be limited to all
35 the details of construction herein shown and described, but what I do claim is:—

1. In a device for drying matrices, the combination of a heating table having a plane surface for receiving the forms, and a shoe located adjacent to said surface and having means for engaging the blankets, said shoe being yieldingly pressed toward the surface of the table.

2. In a device for drying matrices, the combination of a heating table having a plane surface for receiving the forms, and a shoe located adjacent to said surface and substantially parallel having a finished surface on the side toward the table.

3. In a device for drying matrices, the combination of a heating table having a plane surface for receiving the forms, a shoe located adjacent to said surface and substantially parallel therewith, and a movable member adapted to travel along the pressing surface of the shoe at the same rate as the form travels along the table to reduce the friction.

4. In a device for drying matrices, the

combination of a heating table having a 65 plane surface for receiving the forms, a shoe located adjacent to said surface and substantially parallel therewith, and a movable member adapted to travel along the pressing surface of the shoe at the same rate 70 as the form travels along the table to reduce the friction, said member having a portion adapted to yield in a direction normal to the surface of said shoe.

5. In a device for drying matrices, the 75 combination of a heating table having a surface for receiving the forms, a shoe located adjacent to said surface and substantially parallel therewith, a pressure transmitting plate adapted to rest on the blankets for receiving the pressure from said shoe having a portion adapted to yield in a direction normal to the surface of said shoe, and a traveling member between the shoe and said plate for reducing the friction. 80

6. In a device of the character described, the combination of a heating table, a shoe spaced therefrom for holding a form thereon, and resilient means for transmitting pressure from the shoe to the form. 90

7. In a device of the character described, the combination with a form for holding a matrix and drying blankets, of a plate adapted to rest on said blankets and having means for holding it in position, and a plate 95 yieldingly supported thereon.

8. In a device of the character described, the combination of a form for holding a matrix and drying blankets, of a plate adapted to rest on the said blankets and having means for holding it in position, a plate yieldingly supported thereon, and means for limiting the upward motion of the last named plate. 100

9. The method of drying a matrix which 105 consists in placing it on a form, moving the form along a heated surface, and simultaneously applying pressure to the matrix during its travel.

10. In a drying device the combination of 110 a heated table for supporting an article to be dried, with a traveling member supporting and carrying a pressure plate, said member being movable into a position to bring the pressure plate into contact with an article on the table and to move it along the table therewith.

11. In a drying device the combination with a heated table for supporting a series 115 of articles to be dried, of an endless traveling member having a strand above the table, a plurality of pressure plates carried by said traveling member, whereby they will be moved by the member into contact with the articles on the table, and means for moving 120 the articles along the table with the pressure plates.

12. In a drying device, the combination

with a heated table for supporting articles to be dried, of means for moving the articles therealong, a fixed member spaced from the table, a shoe below said member, headed 5 studs for supporting the shoe therefrom, and springs between the fixed member and shoe.

13. In a device of the character described,

the combination of a pressure plate, a blanket below it, a clamp on the plate for 10 holding the end of the blanket, and an eccentric oscillatable rod connected with the clamp for operating it.

In testimony whereof I have hereunto affixed my signature.

HENRY A. WISE WOOD.
